(57) **CLAIM**

The ornamental design for a weed puller, as shown and
described.

DESCRIPTION

FIG. 1 is a front perspective view of a weed puller, showing
my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view thereof;

FIG. 10 is an enlarged detail view of area 10 in FIG. 1;

FIG. 11 is an enlarged detail view of area 11 in FIG. 1; and,
FIG. 12 is an enlarged detail view of area 12 in FIG. 1.

The broken lines in the drawings illustrate the portions of the
weed puller, which form no part of the claimed design.

The dash-dot-dash broken lines encircling the enlarged
views are for annotative purposes only and form no part of
the claim thereof.
